CLAIM

The ornamental design for a vehicle side mirror, as shown and described.

DESCRIPTION

FIG. 1 is a perspective view of a vehicle side mirror;

FIG. 2 is a back view thereof;

FIG. 3 is a front view thereof;

FIG. 4 is a left side view thereof;

FIG. 5 is a right side view thereof;

FIG. 6 is a top view thereof; and,

FIG. 7 is a bottom view thereof.

The broken lines in the drawings indicate a boundary between claimed and unclaimed portions, and form no part of the claim.

The claim includes a second embodiment comprised of a mirror image of a vehicle side mirror as shown in FIGS. 1-7.
